UNITED STATES PATENT OFFICE.

LEON SCHAEFFER, OF SULPHUR, OKLAHOMA.

DESIGN FOR A SURGICAL INSTRUMENT.

Application filed November 2, 1925. Serial No. 15,327. Term of patent 14 years.

To all whom it may concern:

Be it known that I, LEON SCHAEFFER, a citizen of the United States of America, residing at Sulphur, in the county of Murray and State of Oklahoma, have invented a new, original, and ornamental Design for a Surgical Instrument, of which the following is a specification, reference being had to the accompanying drawing, forming a part hereof.

In the drawing:

Figure 1 is a side elevation of a surgical instrument showing my new design, and Fig. 2 is an end view.

I claim:

The ornamental design for a surgical instrument, as shown.

LEON SCHAEFFER. [L.S.]
